MATERNITY CORSET

Irving R. Versoy, New Haven, Conn., assignor to
 The Berger Brothers Company, New Haven,
 Conn., a corporation of Connecticut

Application January 24, 1938, Serial No. 186,561

2 Claims. (Cl. 2—27)

This invention relates to corsets, and more particularly to a corset for maternity wear. The requirements for a satisfactory garment of this type are many and varied, which is evidenced by

5 the many attempts to produce superior garments which will meet the demands made upon them. Among other things, such a garment should give the proper support from below to the abdominal region of the body. In addition, there should be 10 no downward pressure on the body such as might be caused by tight confinement of the region above the abdomen. Moreover, the upper portion of the garment should be expandable so as to avoid the application of pressure, but at the same time confine the flesh of the wearer just 15 enough to prevent bulging and give a comparatively smooth appearance, and at the same time allow for enlargement or growth. The lower part of the garment, while being adjustable in size, should be relatively inelastic so as to give 20 the proper support from below. In addition to these requirements, it is, of course, advantageous to supply, if possible, a single garment which may be worn during the maternity period so as to 25 avoid the necessity of having to purchase several corsets as the period advances. Moreover, the appearance of the garment is important, as it is desirable to give the wearer as nearly as possible a "dress" corset which, while entirely satisfactory 30 from a physiological standpoint, will not be unsightly or cumbersome.

One object of the present invention is the provision of a maternity corset which will be of attractive appearance and at the same time provide 35 the necessary support and confinement for various parts of the body of the wearer.

A further object of the invention is the provision of a maternity corset which will satisfy the requirements noted above, and which will be 40 relatively inexpensive to manufacture and of pleasing appearance.

A still further object of the invention is the provision of a maternity garment which will give the proper support to the abdomen from below, 45 and sufficient freedom to the portions of the body above the abdomen, and which will at the same time present a neat and dressy appearance and be adjustable as to size so that it may be worn during the greater part of the maternity period.

To these and other ends the invention consists in the novel features and combinations of parts to be hereinafter described and claimed.

In the drawings:

Fig. 1 is a front elevational view of a corset

embodimenting my invention, the corset being shown in the position in which it is worn;

Fig. 2 is a front elevational view of the garment in partly open position;

Fig. 3 is a view of the interior of the corset 5 completely open, the belt being omitted for the sake of clearness;

Fig. 4 is a partial elevational view of one side of the front of the garment;

Fig. 5 is an enlarged fragmentary sectional 10 view on line 5—5 of Fig. 4; and

Fig. 6 is a detail view of one of the stays or flexible stiffening members which may be used adjacent the lacings.

To illustrate a preferred embodiment of my 15 invention, I have shown a corset which comprises a back section 10 and adjacent side sections 11 and 12, at the lower portions of which may be gores 13 and 14 of elastic material such as a relatively firm elastic webbing. It will be understood that, with the exception of the gores 13 and 14, the parts heretofore described will preferably be of non-elastic material.

The front portion of the garment comprises front panels 15 and 16 adjustably secured together 25 by the front lacing 17, which extends from top to bottom of the garment. At the edge of the portion 16 are provided a series of fastening members such as hooks 18, which cooperate with eyes 19 upon the free edge of the side portion 12 to 30 hold the garment in proper closed position upon the body of the wearer. The garment may, therefore, be termed a "front lace corset", opening at one side of the exact center, the lacing 17, as shown, being located substantially at the center of the front portion.

Suitable stays 20 are provided, as desired, in the back and side portions of the garment, and at certain of these stay seams are secured flaps 21 and 22, carrying buckles 23, designed to receive the straps 24 secured at each end of an abdominal belt or support 25. This abdominal belt is of the character shown more especially in Fig. 2, and is provided with stiffening stays 26 which diverge slightly upwardly in order that the supporting portion of the belt follow the shape of the body. Adjustment of the belt for size is, of course, permitted by the straps 24 and buckles 23. It may also be noted that, in the preferred form shown, these straps are situated entirely 45 within the corset body, the belt 25 and straps 24, as well as the flaps 21, being covered by the front and side portions of the garment when the latter is closed, or in the position in which it is 50 worn, and is shown in Fig. 1.

It will be noted that the flaps 21 and 22 are secured to the garment at the junction of the back portion 10 with the side portions 11 and 12, so that the support afforded the body by the belt 25 is carried entirely by this belt and the back portion 10 of the garment. As this portion of the garment, and also the belt, are of inelastic material, this will provide a firm and inelastic support for the abdomen from below, which is 10 considered the most desirable practice.

Vertical openings or slots are provided in the side portions 11 and 12. These openings extend from the upper edge of the garment down to a point in the region of the groin, the edges of the 15 openings being held together by elastic lacings 27 and 28. The construction of this portion of the garment is shown more especially in Figs. 4 and 5, from which it will be seen that eyelets 29 are provided at the edges of these openings. It 20 will be observed, however, that the eyelets project outwardly from the edges of the openings intermediate the thickness of the garment, there being several layers of material both above and below them. The result of this arrangement is 25 to depress the eyelets below the upper surface of the garment so that the laces themselves do not overlap the edges of these openings, but lie within the openings substantially flush with the outer surface of the garment in order to present a neat 30 appearance and provide a less bulky arrangement.

Flexible stiffening members 30 are provided at each side of these openings from the groin through the top of the garment, these stiffening 35 members being secured over the base of the eyes so as to set the latter inwardly from the outer surface of the corset and prevent the collapse of the garment at the edges of these openings, or, in other words, to maintain the edges of the 40 openings in smooth, unwrinkled condition.

The laces 27 and 28 are, as stated, preferably of elastic material, so as to permit distention and wider separation of the edges of the side openings at any point in their length, as required. That 45 is, if necessary under conditions of wear, the edges of these openings may be drawn further apart intermediate their ends than they are at the top and bottom. In order to provide additional freedom in this respect, the stiffening 50 member 30 at each side of the opening will preferably be of a character to permit flexibility laterally as well as outwardly and inwardly. That is, these stiffening members will preferably be flexible transversely of their lengths, in the plane 55 of the garment, as well as outwardly and inwardly, or in a plane at right angles to the garment. This will permit a spreading of the edges of the side openings at any point in their length without causing buckling of the stiffening members, 60 as would be the case, for example, if a stay were used which was flexible in one direction only. These stiffening members may be of the character shown in Fig. 6, and consist of a wire tempered and bent into sinuous form. I do not 65 wish to restrict myself in this particular, however, as any stiffener which is flexible in both directions may be used. From the above description it will be apparent that these side openings, constructed in this way and having their edges 70 held by elastic lacings, will provide considerable freedom and expansibility wherever that is required, while at the same time the garment will effect the proper confinement of the flesh of the wearer and hold it in place without applying any 75 downward pressure upon the body. At the same

time the eyelets through which the laces are threaded are depressed below the surface of the garment so that a neat and smooth appearance will result, and no bulging of the outer garments of the wearer at these points will be caused.

The front panels 15 and 16 of the garment will also be secured by elastic lacings, and the construction of the edges of these panels adjacent the lacings may be the same as that described in connection with the side openings, that is, the eyelets 31 which receive the lacing 17 may project from the edges of these portions of the corset in a position depressed from the outer surface, so that the lacing when in place will be substantially flush with the surface of the garment and 15 not project outwardly therefrom. The elastic lacing at this point also permits the front of the garment to follow closely the shape of the body of the wearer, as it permits the opening between the portions 15 and 16 to adjust itself as to width 20 to the wearer's body. That is, this opening may be wider or narrower at any point in its length, according to requirements. Stiffening members 32 and 33 may also be provided at each side of the lacing 17.

As has already been stated, the garment, except for the gores 13 and 14, and the elastic lacings, will preferably be made of inelastic material. This, as will be obvious, provides a firm, inelastic, upwardly acting support for the abdomen by means of the back portion of the garment and the belt 25. At the same time this belt will be completely covered, so that in appearance the garment is a "dress" corset, the front portion of the garment, however, being provided with side 35 openings, the edges of which are held together by elastic lacings, and which extend from the groin upwardly and prevent any harmful downward pressure upon the body, and exert just sufficient pressure to hold the flesh of the wearer in place 40 in a comfortable manner. Likewise, the elastic lacing 17 at the front of the garment provides expansibility from top to bottom at this point, and the lacings exert only sufficient pull on this part of the garment to cause it to lie smooth 45 and conform properly to the body, the support being effected entirely by the belt and not by the outer front section.

The elastic gores 13 and 14 provide necessary freedom over the thighs of the wearer, and preferably extend upwardly only to a point substantially opposite the lower ends of the openings closed by the lacings 27 and 28, so that they do not interfere with the action of these laces, and also do not interfere with the support of the belt. 55 It may be also noted that the arrangement of the eyes in a position projecting from the edges of the openings in which they are disposed provides that the total length of the lacing required will be shorter than if it was necessary for the 60 lacings to overlap the edges of the openings.

While I have shown and described a preferred embodiment of my invention, it will be understood that it is not to be limited to all of the details shown, but is capable of modification and 65 variation within the spirit of the invention and within the scope of the appended claims.

What I claim is:

1. A maternity corset provided with a solid inelastic back portion and with side portions extending forwardly therefrom and with a front portion interconnecting the side portions, said side portions being provided at their lower front parts with elastic gores, said side portions having slot-like openings extending through the 75

5 upper edges thereof and terminating in inelastic parts of said side portions, the lower ends of said openings being offset slightly in a rearward direction from the upper extremities of said gores, and elastic lacings interconnecting the edges of each of said openings whereby the front portion of the corset at the upper part thereof is adapted to adjust itself to the conformation of the body, and stiffening members flexible in the plane of the garment adjacent the openings located with-
10 in the corset body at the respective sides of said openings, said corset being adapted to exert encircling pressure and support in a region adja-
15 cent the lower ends of said openings.

front portions adapted to effect encircling pressure on and support of the body in a region ad-
10 jacent the hip line, said corset having elastic gores the upper ends of which terminate slightly short of said region, the side portions of the 5 corset having slot-like openings disposed some-
15 what rearwardly of the upper extremities of the gores, with the upper ends of the openings open at the upper edge of the corset, elastic lacings interconnecting the edges of each of said open-
10 ings, and flexible sinuous stiffening members located within the corset body at the respective sides of said openings.
